CLAIM

I claim the ornamental design for eyes for plush toys, as shown and described herein.

DESCRIPTION

FIG. 1 is a perspective view of my eyes for plush toys design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines illustrate portions of the eyes for plush toys and environmental structure. None of the broken lines form part of the claimed design.

1 Claim, 4 Drawing Sheets---
